UNITED STATES PATENT OFFICE.

JOHN S. FARMER, OF CANTERBURY ROAD, KILBURN, AND EDWARD TYER,
OF No. 4 OLD STREET, FINSBURY, ENGLAND.

IMPROVEMENT IN ELECTRIC RAILWAY-SIGNALS.

Specification forming part of Letters Patent No. 170,540, dated November 30, 1875; application filed
May 24, 1875.

To all whom it may concern:

Be it known that we, JOHN STINSON FARMER, of Canterbury Road, Kilburn, in the county of Middlesex, England, and EDWARD TYER, of No. 4 Old Street, Finsbury, in the county of Middlesex, England, have invented an Improvement in Signals for Railways; and do hereby declare that the following description, taken in connection with the accompanying drawings, hereinafter referred to, forms a full and exact specification of the same, wherein we have set forth the nature and principles of our said improvement, by which our invention may be distinguished from others of a similar class, together with such parts as we claim and desire to secure by Letters Patent—that is to say:

Our invention relates to combined mechanical and electrical apparatus for working and controlling the semaphore-signals of railways, so that from one or more distant stations these signals can be kept at or set to their "danger" attitude independently of the signalman who usually works them, and that they cannot be set to their "safety" attitude by the said signalman unless all the persons at the distant places agree that this may be done.

By working and controlling the signals in this manner the traffic of the railway can be conducted more effectually on the block system, because by the means which we will describe a signalman at a distant station can not only apprise the signalman at the near station that the line is blocked, instructing him thereby to put his signal at "danger," but can actually put the said signal to "danger," or keep it at "danger" until the line is so far clear that the danger-signal may be taken off; and not only may the signalman at one distant station effect this, but two or more signalmen may have it in their power thus to control a signal, every one of them being enabled to put it to or keep it at "danger" independently of all the others, and it being necessary that all of them should agree before the signal can be put to "safety;" also, this controlling effect can be produced by our apparatus not only from signal-stations, but also from any parts of the line, so that, in case

of any such parts being blocked by accident, or for repair or other purposes, the signals commanding the traffic of such blocked parts can be worked and controlled in the manner set forth.

The apparatus which we employ for this purpose is susceptible of various modifications in its form and arrangements; but these modifications are all dependent for their action on certain general principles, which we will briefly state before we describe more particularly the methods by which we practically apply them.

At the lever usually employed to work the signal, or on the signal-post, or in any convenient part of the rods, wires, or other pulls which connect the lever to the signal, we provide a connection, which can be made or broken, so that in the one case, when the connection is made, the signal can be worked by the lever in the usual way, the signalman having it then in his power to move it to "danger" or to "safety," as he may desire; but in the other case, when the connection is broken the lever is rendered inoperative on the signal, which, being biased by a counter-weight, will rise to or remain at its "danger" attitude, the signalman having no power to move it to "safety." This making or breaking of the connection between the signal and its lever is effected by means of electricity transmitted through coils of electro-magnets, so as to cause them to attract, or, by the cessation of the electric current, to fail to attract, armatures which act upon catches, engaging them together under the one set of electrical conditions, or disengage them from each other under the other set of electrical conditions, and the transmission or cessation of these electrical currents is governed by means of contact-keys at the distant stations, and is indicated upon indicators at these stations, as well as at the signal-station itself, so that all the persons having partial control over the signal can at any time know whether the signal is free to be worked, or whether, by the action of one or more of their number, it is kept at "danger."

It may be readily understood that apparatus embodying these general principles could

be arranged to act either by the transmission or the cessation of electric currents. We prefer, however, in all cases, to arrange it so that the transmission of an electric current is necessary in order that the lever may be operative on the signal, the cessation of such current having the effect of breaking the connection, or rendering the lever inoperative on the signal. This is the safer mode of working, because according to this mode the accidental cessation of the current can only have the effect of stopping the traffic by raising the signal to "danger," or keeping it at "danger." Nor does working in this manner necessarily involve constant expenditure of electrical force, for we can so arrange the apparatus, as we will hereafter explain, that the electrical circuit is completed only at such times as the signalman may desire to lower the signal to "safety." If, then, it is completed by contact made not only at the signal-station, but also at all the other places in the circuit, the signalman will have power to lower his signal; but if at any one of these places the circuit is interrupted, the signalman will have no such power, and the signal will remain at "danger," if that were its previous attitude, or it will rise to "danger" if it previously stood at "safety."

Having thus stated, generally, the means which we employ to produce the desired effect, we will now describe in detail a form of apparatus whereby electricity is, according to our invention, caused to make or break the connection between the signal and its lever, referring to the accompanying drawings and to the figures and letters marked thereon.

Figure 1 represents diagrammatically two block-stations, A and B, at some distance apart on a line of railway, with a semaphore-signal, S, near the one station, which can be lowered to "safety" by a signalman at A, when the signalman at B permits it, but which can be raised to or kept at "danger" by the signalman at either A or B. Fig. 2 shows, to an enlarged scale, a section of the signal-box A, with the usual signal-lever L therein, and the connections from the said lever to the semaphore S. Fig. 3 is a part section to a still larger scale through the frame of the point and signal-levers in the box A, showing our improved apparatus for the connection or disconnection of the lever L and the signal-pull P; and Figs. 4 and 5 are similar sections, showing the said apparatus in different conditions of its action. Fig. 6 is a front view of the electrical make-and-break indicator I in the signal-box B, by means of which the signalman there is enabled to act on the apparatus in A—Fig. 7 representing to an enlarged scale an indicating portion of the said indicator.

It will be seen from Figs. 1, 2, and 6 that an electrical wire, W, communicating with earth X at the station B, passing through the indicator I in the signal-box B, is led along the line to the apparatus in A, and, after pass-

ing through an indicator, J, in the signal-box A, communicates again with earth at X'. The indicator I has a knob or button, i, by turning which the continuity of the wire W can be completed or interrupted in the usual way, a small disk, i', on the stem of the button being turned with the stem, so as to present through a hole in the case of I words such as "free" or "locked," according as the circuit is completed or broken. A battery being placed in any convenient part of the circuit, when the signalman at B turns the button i so as to present the word "free," thereby completing the circuit, a current of electricity passing along the wire W acts, as will presently be described, on the lever apparatus in A, and at the same time causes the small indicating-semaphore of I to stand at "safety," as shown in Fig. 6.

The indicator J is similar to I, except that it has no make-and-break knob, and its small indicating-semaphore also shows "safety" when the circuit is completed. When, on the other hand, the signalman at B turns the knob i so as to present "locked" at the hole of the indicator I, then, the electrical circuit being broken, there is no action on the lever apparatus in A, and the small semaphores in I and J take the "danger" attitude.

Besides the one make-and-break indicator I in the signal-box B, there may be others situated at different parts of the circuit W, and it is to be understood that the circuit can be broken at any one of those, and that there is, therefore, electrical action on the lever apparatus in A only in the case when the current is completed at all such indicators. Moreover, should the battery-power fail, or the wire W be broken, then also the electrical action on the lever apparatus in A will cease. Referring, now, to Figs. 3, 4, and 5, in which the same letters are employed to indicate like parts, the usual hand-lever L, for working the signal, is connected by a rod, l, to a secondary lever, C, on which there is hung by a pivot a catch, c, with a tail projecting upward a little above the upper edge of the lever C. Another lever, D, pivoted on the same fulcrum as C, has the chain, wire, or rod P, for pulling down the semaphore S, attached to it. This chain, wire, or rod we shall hereafter call the pull, which, on being drawn upward, has the effect of lowering the semaphore-arm S to its "safety" attitude, but which, when it is slackened down, permits the semaphore to be raised by a counter-weight to its "danger" attitude.

Above the levers C and D is pivoted a third lever, E, which has on it an iron hammer-head, e. An electro-magnet, M, is fixed in such a position that when the lever E is raised its hammer-head e bears against the poles of the magnet M as an armature, the weight of the lever and its head being so disposed with reference to its pivot that when it is raised, as shown in Figs. 3 and 4, the center of gravity is nearly but not quite vertically over the pivot, and consequently a very moderate attractive force of the magnet M serves to re-

tain the lever E in its upright attitude. If, however, there should be no such attractive force, then the lever E will fall to the position shown in Fig. 5, its head e striking the tail of the catch c. This catch is so made and hung that when left free it engages with the nose of the lever D, and in that case, when the lever L is pulled over, as shown in Fig. 4, raising the lever C, the lever D is raised with it, and the pull P being drawn upward, the semaphore S is lowered to "safety." When, however, the head e bears on the tail of the catch c, disengaging it from the nose of D, as shown in Fig. 5, then the levers L and C may be moved without affecting D, which remains down, the pull P then permitting the semaphore S to take and remain in its "danger" attitude. On the lever C there is another balanced catch, f, having at its upper end a gab, that engages with a pin, n, on the lever E. This pin has a certain freedom of motion in an oblique slot, being kept up toward one end of it by a spring, o.

When the levers C D E are all down, as in Fig. 5, then the catch f is engaged under the pin n, and on the lever L being pulled over, so as to raise C, the lever E is raised through a much greater angle, so that its head e reaches the poles of the magnet M, a stop, N, being provided in the framing to prevent E from going too far.

From the construction which we have described it will now be understood that as long as the electro-magnet E, the coils of which are in the circuit of W, is rendered active by a current of electricity, its attraction holds to its poles the head e, and the levers C and D being then engaged together by the catch c, the semaphore S can be raised or lowered by the movement of the lever L; but as soon as the attraction of the magnet M ceases by the cessation of the electrical current through its coils, then e will drop if it has been raised, or will not be held up, as in Figs. 3 and 4, but will fall, as in Fig. 5, disengaging or keeping disengaged the catch c from the lever D, in which case the semaphore S rises to or remains at danger. This is the result of interrupting the electrical current anywhere in its circuit, taking it out of the power of the signalman at A to lower the semaphore by means of his lever L, or, if it should have been lowered by the lever L, disconnecting it therefrom, so that it is immediately raised by its counter-weight to "danger." As, in order to secure this result, it would be necessary to main-

tain an electrical current constantly in the wire W, except when the circuit is casually interrupted, there would be an unnecessary expenditure of electrical force during the ordinary working of the line, such force being maintained even when there may be no occasion to lower the signal.

In order to economize the expenditure of electrical force we connect the wire W not directly to earth from the coils of the magnet M, but through an insulated spring-contact, T, whereby the circuit is completed only when the lever E is raised, as in Figs. 3 and 4, a projection, e', on the said lever being then brought to bear on the spring T, so as to make contact. Thus it is only when the lever L is moved so as to lift the lever E that the electrical force is passed through the circuit. At all other times, while E remains down, the circuit is broken at T, even when it is completed at all other parts of the line.

Having thus described the nature of the said invention, and the best means we know of carrying it into practical effect, we hereby declare that we do not claim any mode of applying electricity to give movement to a railway-signal, or to release mechanism which, by power previously stored up, is permitted to act for the purpose of moving a railway-signal; but

We claim—

1. The combination of the counterweighted semaphore and hand-lever with an interposed mechanism, consisting of the levers C D E, catches c and f, connections l and p, magnet M, and wire W, as and for the purposes described.

2. The combination, for effecting the connection or disconnection of the lever and signal, of the levers C D E and catches c and f with the electro-magnet M, and wire W, and make-and-break indicator I, substantially as herein described in reference to the accompanying drawings.

3. The combination of the spring-contact T with the lever E, for the purpose of economizing the electrical force, substantially as herein described.

In testimony whereof we have signed our names to this specification in the presence of two subscribing witnesses this 10th day of May, 1875.
